UNITED STATES PATENT OFFICE.

ABRAHAM NOVICK, OF NEW YORK, N. Y., ASSIGNEE TO F. L. SCHMIDT COMPANY, OF NEW YORK, N. Y., A CORPORATION OF NEW YORK.

WASHER AND STRING ATTACHING MACHINE.

1,255,558.

Specification of Letters Patent.

Patented Feb. 5, 1918.

Application filed April 2, 1917. Serial No. 159,142.

To all whom it may concern:

Be it known that I, ABRAHAM Novick, a citizen of the United States, and resident of the city of New York, in the county of Kings and State of New York, have invented certain new and useful Improvements in Washer and String Attaching Machines, of which the following is a specification.

This invention relates to machines for attaching washers and strings to envelopes and the like.

That point on the machine where the operating punch and anvil fasten or set the washers and string to the envelop is hereinafter called the setting position.

The object of this invention is the provision of simple means for feeding a bottom washer into the setting position from a point distant from said setting position.

20 A further object of this invention is the provision of means for forming a finished bottom washer of the desired shape from a continuous web of paper at a point distant from the setting position.

25 By placing the bottom washer forming and feeding means at a distance from the setting position, I am enabled to form a washer without increasing the complexity of the mechanism situated at the setting position and without increasing the danger to the fingers of the operator present in machines previously made.

I accomplish the aforesaid objects by the mechanism shown in the preferred form in the accompanying drawings, in which—

Figure 1 is a front elevation of my improved machine. In this figure all of the means for operating the various sub-mechanisms are not shown, since they can be provided by one skilled in the art to which this invention pertains.

Fig. 2 is a side elevation of my machine, partly in section.

Fig. 3 is a top view of the bottom washer forming means and Fig. 4 is a cross section of the same, showing the means for reciprocating the slide.

Fig. 5 is a vertical section of the bottom washer forming means in its operative position and Fig. 6 is a similar view of the same at the completion of the washer punching operation, showing the finished washer being stripped from the pin.

Fig. 7 is a section through the center of the eyelet, showing the eyelet, washers and string 55 attached to an envelop or sheet of paper.

Fig. 8 is a vertical section of the top washer receptacle and delivery means showing the means for delivering a top washer with a string therethrough into setting position.

It is intended that the improved mechanism shown and described in the present application be used in connection with my invention shown and described in patent 65 numbered 1,104,128, to which reference is to be made for details of construction and operation.

My present invention comprises mechanism for delivering a top washer, a string 70 and an eyelet into setting position, a washer forming device and mechanism for carrying the washer from the cutting to the setting position and mechanism for fastening the washer and string to the envelop or sheet by 75 means of the eyelet.

The center of the setting position is the center line of shaft 1, which is journaled in lugs 2 and 3 of frame 4. Said shaft is reciprocated by means of lever 5, pivoted at 6 on frame 4 and slidably attached to the shaft by pin 7 acting in slot 8. Connecting rod 9, operated from a cam not shown on cam shaft 10, is attached to the end of lever 5 for oscillating said lever for reciprocating shaft 1. 85 The lower end of shaft 1 is made hollow to receive spring 11 and eyelet punch 12. Eyelet engaging needle 13 passes through punch 12 and is acted on by spring 11 which tends to maintain said needle in its lowest position.

Arm 14 of frame 4 has at its outward extremity anvil 15 against which the lower end of the eyelet 16 is flanged on the downward movement of shaft 1, thereby fastening 95 washers 17 and 18 against the sheet or envelop 19, said anvil 15 being in vertical alignment with eyelet punch 12.

Eyelets 16 are fed to the setting position through hopper 20 to which is attached eyelet chute 21 for feeding the eyelets one at a time. Cam 23 is attached to said chute and hopper and causes the chute to oscillate about pivot 22 on frame 4. Clamp 24 is fastened to shaft 1 and moves vertically therewith. Cam roll 25 held in clamp 24 operates

cam 23 and therethrough chute 21, on the movement of shaft 1.

A stack or reservoir 27 of top washers is supported by hollow rod 28 held in arm 102 5 attached to lug 2 through which rod string 29 is threaded from a spool not shown, supported from frame 4. Stack 27 passes through cylindrical support 30, which is attached to lug 3 of frame 4. Top washer 10 slide 31 is arranged for reciprocation in the flattened base of support 30 and is indented 15 to receive one washer at a time from stack 27 which rests on said slide, string 29 passing through a suitable opening in said slide 20 and extending past the setting position any given distance as desired. For reciprocating slide 31 and feeding one top washer at a time from the stack to setting position lug 25 connects said slide with top washer feed 25 lever 33 mounted on rock shaft 34. Said shaft is journaled in suitable bearings extending from frame 4 and is rocked by crank 35 and rod 36 connected thereto, said rod being operated from cam shaft 10 by a suitable cam not shown.

For forming the bottom washers and forwarding said washers into setting position, a cutting mechanism and a step by step slide are mounted on guide table 37 attached 30 to frame arm 14. (Figs. 1 and 2.) The roll of paper 39 is revolvably mounted on arm 38 outstanding from frame 4, said roll being of slightly greater width than the washers required. The strip or web of paper 40 is 35 threaded through punch bearing 41 which has an opening 42 for the paper to pass through. Extending frames 43 outstanding from bearing 41 are attached to guide table 37 and support said bearing therefrom. Said extending frames 43 support shafts 44 and 45 therein. The paper forwarding rolls 46 and 47 are mounted on shafts 44 and 45 respectively and are operated by gears 48 and 49 on the same shafts. On shaft 45 is 45 ratchet wheel 50 operated through pawl 51 and rod 52, said rod being driven from a cam not shown on cam shaft 10. Washer punch 53 is mounted for reciprocation in bearing 41 and has a hole 54 therein of sufficient diameter to receive pin 55. Said pin 55 is attached to guide 37 and is adapted for cutting the center hole in the bottom washer. Link 56 is pivoted at one end to punch 53 and at the other to lever 5, thereby reciprocating said punch on the oscillation of said lever. Bottom washer die plate 57 is attached to punch bearing 41 and has a hole 58 therein for co-operating with punch 53 for cutting a disk from the web of paper 40. Stop pin 59 is inserted in guide 37 at a distance from cutter pin 55 slightly greater than the radius of the bottom washer for preventing rearward movement of said washer while it is being removed from said 65 pin.

Slide 60 is mounted for reciprocation forwardly and rearwardly in guide 37. A sufficient number of indents 62 of suitable shape to hold the washers against rearward movement relative to the slide, are cut in 70 said slide. Both ends of the slide have their center portions cut away to form slots 63 and 64 to allow said slide to pass pin 55 and anvil 15 on the rearward and forward reciprocations of said slide respectively, the 75 beveled edge 61 at the rear end of said slide being adapted to pass underneath a washer which may have been pressed on to pin 55. Levers 65 mounted on shafts 66 in bearings 69 located on guide 37 are held down against a guiding groove 67 in slide 60 by means of springs 68 and are adapted to engage the bottom washers preferably at the center holes thereof. A stop pin as 70 may be used to prevent the rear lever from dropping into 80 slot 63. Slide 60 is reciprocated by rod 71 attached at one end to pin 72 extending from slide 60 and passing through a slot in guide 37, said rod 71 being attached at its other end to bell crank lever 73. Said lever 73 is 85 mounted on shaft 74 in frame 4 and is operated by rod 75, through cam 76 on cam shaft 10.

The operation of my improved machine is 90 as follows:

It being assumed that a controllable one revolution clutch is attached to cam shaft 10, motion may be imparted to the various sub-mechanisms, which are properly timed as hereinafter described.

When shaft 1 is in its highest position, eyelet and washer engaging needle 13 is extended its greatest distance therethrough, and cam roll 25 is in contact with the low part of eyelet chute cam 23, thereby allowing the lower end of said chute to present an eyelet into setting position, the lower end of said needle 13 being above the lower end of said chute. The upper part of cam 23 is so shaped that a vertical downward movement 105 of shaft 1 sufficient to cause needle 13 to engage an eyelet presented by said chute, ceases no movement of said chute.

At the same time, top washer slide 31 is in its farthest extended position horizontally, having taken a washer from the bottom of stack 27 and presented said washer with string 29 passing therethrough into setting position.

Washer punch 53 is at this time in its 120 lowest position (Fig. 5) having just formed a bottom washer from web of paper 40 and pressed said washer over cutting pin 55, thereby cutting a center hole in said washer and leaving said washer mounted on said 125 pin. Slide 60 is in its extreme forward position and presents a bottom washer into setting position, anvil 15 being in slot 64.

Envelope or sheet 19 being inserted between top washer slide 31 and bottom washer 130

slide 60, the setting or fastening operation may be completed.

On the upward movement of connecting rod 9, shaft 1 moves downwardly and needle 13 engages the eyelet and the washers presented into setting position, whereupon cam roller 25 moves on to the high part of cam 23, thereby retracting chute 21. At the same time, the top washer slide is retracted by means of rod 36 operated by a suitable cam. Bottom washer slide 60 is also retracted at this moment by the proper movement of rod 71 through cam 76. On the further downward movement of shaft 1, needle 13 engages anvil 15, the eyelet and top washer sliding down said needle on to the sheet or envelop with the string 29 between the washer and the eyelet, the bottom washer sliding down said needle on to the anvil when shaft 1 moves down still farther, eyelet punch 12 engages the eyelet forcing said eyelet through the envelop or sheet and through the holes in the washers into engagement with anvil 15 whereupon the eyelet is flanged and fastens the top and bottom washers and the string to the envelop in the manner shown in Fig. 7. The envelop 19 is then removed by hand from anvil 14 thereby causing a length of string to be pulled through rod 28 past the setting position equal to the distance the envelop is moved before the string is cut. The string attached to the envelop is cut off close to the washer (Fig. 7) manually, a suitable gage being provided, if desired, to enable the operator to pull the same amount of string past the setting position after each operation.

Washer punch 53 has in the meantime been raised to its highest position and slide 60 has been moved rearwardly, the beveled edge 61 passing under the washer on pin 53 (Fig. 6) and stripping said washer from the pin. Stop pin 59 prevents the washer 45 from moving rearwardly, and slide 60 continues its rearward movement until said washer rests in the rear indent in said slide. This completes the cycle of operations.

Repeating the cycle, at the beginning of 50 the next revolution of the one revolution clutch, rod 52 is suitably operated to move paper feed rolls 46 and 47 to feed the web sufficiently for forming a new bottom washer. At the same time, slide 60 is moved 55 forwardly, carrying the finished washer, which has been deposited in the rear indent 62, forward, until said washer is engaged by lever 65, said washer being held against rearward movement on the slide by said indent. 60 On the next rearward movement of the slide, the washer is held stationary by means of lever 65, the slide moving away from under said washer until said washer moves into the next forward indent. The stroke of said 65 slide is slightly greater than the distance be-

tween indents. It will be seen that, using the number of indents illustrated, two complete forward and rearward reciprocations are necessary to forward a washer from the cutting position into the setting position, 70 though it is obvious that as many indents and coöperating levers as desired may be used to span the distance from cutting to setting positions.

I prefer to use a round washer cutting 75 punch, thereby cutting round bottom washers and making the finished bottom more sightly than it appears with a square or rectangular bottom washer.

It is obvious that no departure from the 80 scope of this invention is made if the top washer reservoir and top washer slide and feeding mechanism were replaced with the mechanism shown and described as preferable for bottom washer forming and feeding and vice versa.

Thus, if it is desired to use stacks of washers from one of which the top washer is fed and from the other of which the bottom washer is fed, the mechanism illustrated for 90 feeding the top washer may be used for both. Or if it is desired to cut both top and bottom washers from a continuous web of paper, the means illustrated for forming and forwarding the bottom washer may be used 95 for both top and bottom washers.

What I claim is:

1. In a machine of the character described, means for delivering a top washer with a string therethrough and an eyelet into setting position, means for forming a bottom washer from a continuous web of paper, said washer forming means being located in spaced relation to the setting position, means for forwarding the finished bottom washer 100 into setting position, and means for flanging the eyelet for fastening said washers and string to an envelop.

2. In a machine of the character described, means for delivering a top washer with a 110 string therethrough, and an eyelet into setting position, means for delivering a finished bottom washer from a point in spaced relation to the setting position into the setting position, and means for flanging the eyelet 115 for fastening said washers and string to an envelop.

3. In a machine of the character described, means for forming bottom washers from a continuous web of paper, comprising a reciprocating punch, a stationary die and a stationary pin coacting with said punch 120 for receiving a finished washer, and means for stripping the washer from said pin and for forwarding the finished washer from 125 the cutting position to a setting position.

4. In a machine of the character described, means for forming a washer, means for engaging and forwarding said washer into setting position comprising a reciprocating 130

- slide, a slotted beveled edge at one end of said slide, said slide having indents therein for preventing rearward movement of the washer on said slide whereby the washer is advanced on each forward reciprocation of said slide and means for preventing the rearward movement of said washer with said slide on the rearward reciprocation of said slide.
10. 5. In a machine of the character described, means for forming a washer, means for engaging and forwarding said washer into setting position comprising a reciprocating slide having a slotted beveled edge at one end thereof and adapted for holding washers thereon and for advancing the washers on each forward reciprocation of said slide, and levers coöperating with said slide for engaging the washers on the rearward reciprocation of said slide for preventing rearward movement of said washers with said slide.
15. 6. In a machine of the character described, means for forming bottom washers from a continuous web of paper comprising a reciprocating punch, a stationary die and a stationary pin coacting with said punch, and means for forwarding the finished washer from the cutting position to a setting position comprising a reciprocating slide for stripping the washer from said pin and for advancing the washer at each forward reciprocation into final setting position and means for preventing the rearward movement of said washer with said slide on the rearward reciprocation of said slide.
20. 7. In a machine of the character described, means for delivering a top washer with a string therethrough and an eyelet into setting position, means for forwarding a bottom washer into setting position comprising a reciprocating slide adapted for holding washers thereon and for advancing the washers on each forward reciprocation of said slide, and levers coöperating with said slide for engaging the washers on the rearward reciprocation of said slide for preventing rearward movement of said washers with said slide, and means for flanging the eyelet for fastening said washers and string to an envelop.
25. 8. In a machine of the character described, means for delivering an eyelet into setting position, means for delivering a top washer with a string therethrough into setting position, means for forwarding a finished bottom washer from a position in spaced relation to the setting position into the setting position and means for flanging the eyelet for fastening said washers and string to an envelop.
30. 9. In a machine of the character described, means for delivering a top washer with a string therethrough and an eyelet into setting position, means for forming bottom washers from a continuous web of paper comprising a reciprocating punch, a stationary die and a stationary pin coacting with said punch, and means for forwarding the finished washer from the position where it is cut to the setting position, and means for flanging the eyelet for fastening said washers and string to an envelop.
35. 10. In a machine of the character described, a washer reservoir having a string passage lengthwise therethrough, means for delivering a washer with a string therethrough from said reservoir into setting position, means for delivering an eyelet into setting position means for forwarding a finished bottom washer from a position in spaced relation to the setting position into the setting position, and means for flanging the eyelet for fastening said washers and string to an envelop.
40. 11. In a machine of the character described, means for delivering a top washer with a string therethrough and an eyelet into setting position, means for delivering a finished bottom washer from a point in spaced relation to the setting position into the setting position, a needle for engaging said eyelet and said washers, means for retracting said eyelet and washer delivery means after 70 said needle has engaged the eyelet and washers.
45. 12. In a machine of the character described, means for delivering an eyelet into setting position, means for delivering a top washer with a string therethrough into setting position, means for forming bottom washers from a continuous web of paper comprising a reciprocating punch, a stationary die and a stationary pin coacting with said punch, means for forwarding the finished washer from the position where it is cut to the setting position, and means for flanging the eyelet for fastening said washers and string to an envelop.
50. 13. In a machine of the character described, means for delivering a top washer with a string therethrough and an eyelet into setting position, means for forming bottom washers from a continuous web of paper comprising a reciprocating punch, a stationary die and a stationary pin coacting with said punch, means for forwarding the finished washer from the position where it is cut to the setting position, and means for flanging the eyelet for fastening said washers and string to an envelop.
55. 14. In a machine of the character described, means for delivering a top washer with a string therethrough, and an eyelet into setting position, means for forming bottom washers from a continuous web of paper comprising a reciprocating punch, a stationary die and a stationary pin coacting with said punch, and means for forwarding the finished washer from the position where it is cut to the setting position, and means for flanging the eyelet for fastening said washers and string to an envelop.
60. 15. In a machine of the character described, means for delivering a top washer with a string therethrough and an eyelet into setting position, means for delivering a finished

with said punch, means for forwarding the finished washer from the position where it is cut to the setting position comprising a reciprocating slide for stripping the washer from said pin and for advancing the washer at each forward reciprocation of said slide into final setting position, and means for preventing the rearward movement of said washer with said slide on the rearward reciprocation of said slide, and means for flanging the eyelet for fastening said washers and string to an envelop.

15. In a machine of the character described, means for delivering an eyelet into setting position, means for delivering a top washer with a string therethrough into setting position, means for forming bottom washers from a continuous web of paper, means for forwarding a bottom washer into setting position comprising a reciprocating slide adapted for holding washers thereon and for advancing the washers on each forward reciprocation of said slide, and levers coöperating with said slide for engaging the washers on the rearward reciprocation of said slide for preventing rearward movement of said washers with said slide, and means for flanging the eyelet for fastening said washers and string to an envelop.

30 16. In a machine of the character described, means for delivering an eyelet into setting position, means for delivering a top washer with a string therethrough into setting position, means for forming bottom washers from a continuous web of paper comprising a reciprocating punch, a stationary die and a stationary pin coacting with said punch, means for forwarding the finished washer from the position where it is cut to the position where it is set comprising a reciprocating slide for stripping the washer from said pin and for advancing the washer at each forward reciprocation of said slide into final setting position and means for preventing the rearward move-

ment of said washer with said slide on the rearward reciprocation of said slide, and means for flanging the eyelet for fastening said washers and string to an envelop.

17. In a machine of the character described, a washer reservoir having a string passage lengthwise therethrough, means for delivering a washer with a string therethrough from said reservoir into setting position, means for delivering an eyelet into setting position, means for forming a bottom washer from a continuous web of paper at a point in spaced relation to the setting position, means for forwarding the finished bottom washer from the position where it is cut to the setting position comprising a reciprocating slide for advancing the washer at each forward reciprocation into final setting position, and means for preventing the rearward movement of said washer with said slide on the rearward reciprocation of said slide, and means for flanging the eyelet for fastening said washers and string to an envelop.

18. In a machine of the character described, a washer reservoir having a string passage lengthwise therethrough, means for delivering a washer with a string therethrough from said reservoir into setting position, means for delivering an eyelet into setting position, means for delivering a finished bottom washer from a point in spaced relation to the setting position into the setting position, a needle for engaging said eyelet and said washers, means for reTRACTING said eyelet and washer delivery means after said needle has engaged the eyelet and washers, and means for flanging the eyelet for fastening said washers and string to an envelop.

Signed at New York, in the county of New York and State of New York, this 31st day of March, A. D. 1917.

ABRAHAM NOVICK.
